(57) **CLAIM**

The ornamental design for a hanger bar for a hanger bar assembly, as shown and described.

DESCRIPTION

FIG. 1 is a top, rear, right-side perspective view of a hanger bar in our new design for a hanger bar for a hanger bar assembly;

FIG. 2 is a left-side elevation view thereof, the right-side elevation view being a mirror image;

FIG. 3 is a front elevation view thereof;

FIG. 4 is a rear elevation view thereof;

FIG. 5 is a top plan view thereof; and,

FIG. 6 is a bottom plan view thereof.

1 Claim, 6 Drawing Sheets
